CLAIM

We claim the ornamental design for a wireless sensor without display, as shown and described.

DESCRIPTION

FIG. 1 is an isometric front, bottom view of a first embodiment of a wireless sensor without display;
FIG. 2 is an isometric rear, top view thereof;
FIG. 3 is a back view thereof;
FIG. 4 is a left side view thereof;
FIG. 5 is a right side view thereof;
FIG. 6 is a front view thereof;
FIG. 7 is a top view thereof; and,
FIG. 8 is a bottom view thereof.
